UNITED STATES PATENT OFFICE

158,252

TRIPOD TOP BRACKET FOR SCREENS

Leo J. Du Mais, Chicago, Ill., assignor to Da-Lite
Screen Company, Inc., a corporation of Illinois

Application November 4, 1948, Serial No. 149,461

Term of patent 14 years

(Cl. D61—1)

To all whom it may concern:

Be it known that I, Leo J. Du Mais, a citizen of the United States, residing at Chicago, in the county of Cook and State of Illinois, have invented a new, original, and ornamental Design for a Tripod Top Bracket for Screens, of which the following is a specification, reference being had to the accompanying drawing, forming part thereof.

Figure 1 is a perspective view of a tripod top bracket for screens, showing my new design.

Figs. 2, 3 and 4 are top, bottom and side views respectively thereof.

I claim:

The ornamental design for a tripod top bracket for screens, as shown.

LEO J. DU MAIS.
